Patented Jan. 14, 1919.

UNITED STATES PATENT OFFICE.

CLAIR A. GILSON, OF NILES, MICHIGAN.

GEOMETRICAL AND DRAFTING INSTRUMENT.

1,291,476.

Specification of Letters Patent.

Patented Jan. 14, 1919.

Application filed May 4, 1916. Serial No. 95,369.

To all whom it may concern:

Be it known that I, CLAIR A. GILSON, a citizen of the United States, and resident of Niles, in the county of Berrien and State of Michigan, have invented certain new and useful Improvements in Geometrical and Drafting Instruments, of which the following is a specification.

The present invention relates to new and useful improvements in drafting instruments and more particularly to an improved triangle and protractor.

The primary object of my invention is to provide a combination protractor, integrator, and 30-60° triangle.

My invention contemplates the provision of an improved drafting instrument combining a number of instruments in one and with this end in view I provide a drafting triangle having symmetrical curves associated therewith, irregular curves associated therewith, and angle protracting indicia thereon.

With the above and other objects in view my invention consists in the structure hereinafter described and claimed, the same being shown in the accompanying drawing, in which—

Figure 1 represents a plan view of a drafting instrument embodying the improvements of my invention.

Fig. 2 is a diagrammatic view of the application of my drafting instrument for determining areas.

Referring more particularly to the drawing, wherein similar characters of reference designate like and corresponding parts, 1 designates the body of my improved drafting instrument, said body being of a configuration conforming to the shape of the usual 45° triangle. Along the two shorter sides 2 and 3 of the triangle I provide indicia 4 and 5 indicating in degrees for protracting purposes, said indicia radiating from a point 6 at the base or lower edge 7 of the triangle. It will be readily apparent that the edge 7 is the hypotenuse of the triangular body 1 and when using the device of my invention in its usual capacity said edge will be the base edge. Therefore, I will herein-after term the edge 7 as the base edge of the triangle.

Extending upwardly from the point 6 to the vertex of the triangle I provide a line

8 dividing the body 1 into two right-angle 55 triangles 9 and 10, said line being at 90° relative to a straight edge of the body. The triangles 9 and 10 are provided with openings 11 and 12 of various shapes, the adjacent marginal edges of said openings 60 being in the form of symmetrical curves 13 and 14, respectively. The symmetrical curves 13 and 14 are the major curves of the device one portion of each curve being adjacent the base edge of the triangle 1, the 65 other portions of the curves being arranged on either side of the line 8 and equi-distant therefrom. A plurality of irregular curves 15, 16 and 17 may be provided for obvious purposes. The outer marginal edges of the 70 openings 11 and 12 are straight edges and are designated 18 and 19, the edges 18 being at an angle of 60° with the base edge 7 and the edge 19 being at a 30° angle with the said base edge. This arrangement provides 75 a 75° angle between the edge 18 and the edge 3 of the same triangle and a 15° angle between the edge 19 and the last mentioned edge 3. Thus it will be seen that a plurality of various angular relations may be obtained, the major ones being 30-60°, 15-75° 80 and a 45° triangle. In this manner I provide three angular combinations which would ordinarily necessitate the provision of a number of different triangles. 85

An intermediate curve 20 is provided, said curve 20 being located adjacent the curve 14 hereinbefore referred to, said curve 20 being about the same length as said curve 14. The curve 20 performs the function which will 90 hereinafter appear.

The curves 13 and 14 are so relatively positioned that the shortest distance between these curves at any point multiplied by the height of this point from the base line, is 95 always equal to one square inch. The curves 20 and 14 are so relatively positioned that the shortest distance between these curves to any point multiplied by the height of this point from the base line is always equal to 100 one-tenth of one square inch.

To find the area of the figure D, N, M, K, indicated in the Fig. 2 of the drawings, draw the vertical lines AC and BK and any horizontal line AB. Place the instrument as 105 shown by the dotted line, with the curve 13 of the instrument tangent to the figure at point C marking the point D. Then slide

the instrument on the line AB until the curve 13 comes to D; keeping the instrument to the right of the base. The curve 14 will then give the point E. Move the instrument across the figure, marking the points F, G, H and I, as each space is subtended. To locate the points J and K, the intermediate curve 20 that indicates an area of one tenth of a square inch can be used.

10 The area of the part of the figure which is below the portion of the curve CD is one square inch, as previously stated, the width CD multiplied by the height from the base line is always equal to one square inch. The 15 instrument being moved six times in going from C to I, and twice from I to K, thus gives the area of AB KC as 6.2 square inches. In a similar manner, A, N, M, B, is 2.1 square inches, and the area of the figure is 20 6.2-2.1 which equals 4.1 square inches.

It will thus be seen that in the provision of my improved drafting instrument I have afforded an instrument which embodies in a single device a structure permitting the 25 use of the device in as many as six different capacities, namely, a 30-60° triangle, a 15-75° triangle, an irregular curve, a curve radiator, a 45° triangle, and an area determiner, the last mentioned being for the purpose of determining areas of plane figures.

From the above description taken in connection with the accompanying drawings, it is thought that a clear and comprehensive understanding of the construction and various 35 uses to which my improved drafting instrument may be put will be readily apparent and I reserve the right to make such changes in the relative proportion of the device as do not depart from the spirit and 40 scope of the invention as claimed.

Having thus fully described my invention,

what I claim as new and desire to secure by Letters Patent, is:

1. A drafting instrument of the class described including a triangular body having 45 a dividing line extending from vertex thereof to the opposite base edge, said triangle being provided on opposite sides of said dividing line with openings, the marginal edges of said openings adjacent the base and 50 said dividing line being in the form of symmetrical curves, and said curves being of such shape that the length of the shortest line between any point on one curve and the base multiplied by the length of the line 55 drawn from such point parallel to the base to the other curve is equal to a given area.

2. A drafting instrument of the class described including a triangular body having a dividing line extending from the vertex 60 thereof to the opposite base edge, said triangle being provided on opposite sides of said dividing line with openings, the marginal edges of said openings adjacent the base and 65 said dividing line being in the form of symmetrical curves, said curves being of such shape that the length of the shortest line between any point on one curve and the base multiplied by the length of the line drawn from such point parallel to the 70 base to the other curve is equal to a given area, and an additional symmetrical curve 75 so relatively positioned to one of the first mentioned curves that the length of the shortest line between any point on one curve and the base multiplied by the length of the line drawn from such point parallel to the base to the other curve is equal to a predetermined fraction of the given area.

In testimony whereof, I affix my signature 80 hereto.

CLAIR A. GILSON.
